Attorney

UNITED STATES PATENT OFFICE

JACOB STEIN, OF BROOKLYN, NEW YORK

NETHER GARMENT

Application filed October 15, 1928. Serial No. 312,612.

This invention relates to nether-garments for women and particularly to the chemise type of garment known as "teddies."

An object of the invention is the provision of the usual nether-garment of the above stated character provided with a removable rubber shield having front and back sides connected by a relatively narrow crotch portion, the back side forming a relatively wide seat portion to extend about the buttocks of the wearer, the free ends of said lining being supported from the garment at its waist portions, and readily removable and applicable in position at will so that the nether-garment may be used either with or without said shield.

It is also an object of the invention to provide a nether-garment of the above stated character which employs in combination therewith a rubber inner lining removably suspended from the waist portion of the garment in a manner that will effectively sustain it in position and which will permit its ready removal without requiring buttons, fasteners, and the like, but which is held in position with respect to the garment by the waist contracting means desirable in garments of this type.

With the above and other objects in view, the invention resides in sundry details of construction, combination and arrangement of parts hereinafter more fully described and pointed out in the appended claims.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings which show the preferred embodiment of the invention as at present devised:—

Figure 1 is a perspective view of the garment of this invention;

Figure 2 is a side elevation of the garment;

Figure 3 is a view illustrating the construction of the rubber shield and the position it assumes when on the wearer; and

Figure 4 is a fragmentary detail view showing the manner in which the shield is held in position on the garment.

Referring in detail to the drawings, the nether-garment of this invention has a full loose, short skirt-like portion 10 having its lower edges closed or secured together between the legs of the wearer, as at 12, providing leg openings 11. The garment is formed with a bodice 13 integral with or joined to the skirt portion 10 at or about the waist portion of the garment. The garment is supported from the shoulders of the wearer by usual straps 14 having their ends connected to the upper edges of the bodice 13. In order that the upper edge of the bodice may fit closely above the breasts, it is usually provided with a draw string 15; and, a draw string 16 is usually provided at the point where the bodice and the skirt portion 10 are joined for the purpose of relieving the garment of its fullness about the waist of the wearer and supporting the lower portion of the garment.

An inner shield 18 of impervious material, such as sheet rubber is disposed within the skirt portion 10 and is removably suspended from the waist portion of the garment, in order to protect the nether-garment and outer garments from perspiration or other emissions from the body. In the present form of the invention, the skirt 10 and the bodice 13 are connected together by open work or lace 17 through which the draw string 16 is threaded in an effective and ornamental manner. The end edges of the shield 18 are likewise provided with a strip of lace 19 which is stitched to it in any suitable or approved manner and is laid against the lace 17 of the garment so that the lacing or ribbon 16 may be simultaneously extended through the lace thereof and thereby held in position. Obviously, when it is not desired to use the shield 18, it may be removed by merely withdrawing the lacing 16 from the opening or lace 19 of the lining.

While in this disclosure I have shown lace

17 and 19, the same results may be accomplished by providing the garment and the lining 18 with other suitable openings through which a lacing 16 may be threaded 5 in the manner described. This means of attaching the shield to the garment permits the shield to be positioned and adjusted around the waist portion of the garment as to suit the convenience, comfort and desires 10 of the wearer in a manner as is not permitted by buttons, fasteners and the like which are also objectionable with thin and light fabrics. Further, the present construction permits the crotch portion of the shield to 15 be drawn closer to or away from the body of the wearer by tightening or loosening the draw string or ribbon 16. It will be obvious also that if the string 16 is loosened and suspending loops provided therein at 20 the point where the string is threaded through the openings or lace 19, the upper edges of the shield will lie below the openings or lace 18 in the nether-garment, thus permitting vertical adjustment of the 25 crotch portion of the shield.

The shield 18 is formed of sheet rubber or other impervious material and takes the form of an elongated strip of sheet material having a rear or seat portion *a* of a width 30 sufficient to extend across the buttocks of the wearer, while the crotch portion *b* and abdominal portion *c* are relatively narrower and formed by cutting the edges of the crotch portion on converging lines from the 35 seat portion, the abdominal portion being mainly an extension of the crotch portion and may be slightly wider at its free end.

The garment thus described provides a nether-garment having an adjustable and removable shield for sanitary purposes, which shield may be removed therefrom when desired, thus the garment being capable of being worn at all times. It will also be obvious that a nether-garment of the 45 present construction is devoid of objectionable attaching means for the removable shield as the same is removably supported by the ornamental waist restricting means desirable in garments of this type.

50 Having thus described the invention, what is claimed is:—

1. A nether-garment including a lower trunk covering portion, said garment having a series of circumferential openings about 55 the waist portion thereof, a sanitary shield of impervious material having a series of transverse openings at its ends, and a draw-string threaded through the openings of the waist in the garment and through the openings in said sanitary shield whereby the garment may be contracted about the waist and said shield may be detachably secured in position and rendered vertically adjustable relative to the garment to loosen or tighten 60 the shield against the crotch of the wearer.

2. A nether-garment having a bodice supporting a lower trunk covering portion, said garment having a series of circumferential openings about the waist portion thereof, a sanitary shield consisting of an elongated 70 strip of impervious material having its ends detachably secured respectively to the front and back waist portions of the garment, the ends of said shield having a series of transverse openings therein, a draw-string threaded 75 through the openings of the waist in the garment and through the openings in said sanitary shield whereby the garment may be contracted about the waist and said shield may be detachably secured in position and 80 rendered vertically adjustable.

In testimony whereof I have hereunto set my hand.

JACOB STEIN.
